CLAIM

The ornamental design for a paintbrush handle, as shown and described.

DESCRIPTION

FIG. 1 is a perspective view of the paintbrush handle according to the present invention;

FIG. 2 is an elevational view of one side of the paintbrush handle according to the present invention, the other side being identical thereto;

FIG. 3 is an elevational view of one end of the paintbrush handle according to the present invention;

FIG. 4 is an elevational view of the opposite end thereof;

FIG. 5 is a top plan view of the paintbrush handle according to the present invention; and,

FIG. 6 is a bottom plan view thereof.

The broken lines showing a head and bristles are for illustrative purposes only and form no part of the claimed design.
